UNITED STATES PATENT OFFICE.

CHARLES J. PILLING, OF PHILADELPHIA, PENNSYLVANIA, ASSIGNOR TO
HIMSELF AND GEORGE P. PILLING, OF SAME PLACE.

DESIGN FOR A BLANK FOR SPECULUM-BLADES.

SPECIFICATION forming part of Design No. 33,942, dated January 22, 1901.

Application filed December 26, 1900. Serial No. 41,174. Term of patent 7 years.

To all whom it may concern:

Be it known that I, CHARLES J. PILLING, a citizen of the United States, residing at Philadelphia, State of Pennsylvania, have invented and produced a certain new and original Design for a Blank for a Speculum-Blade, of which the following is a full, clear, and exact description, reference being had to the accompanying drawings, forming a part of this specification.

In said drawings, Figure 1 is a plan view, and Fig. 2 a side view.

My invention consists of the design in novel external outline planular shape or configuration shown of the sheet-metal blank from

which the upper operating-blade of a bivalvular speculum is produced when "struck up" by dies in the usual manner of producing metal shapes from sheet-metal blanks.

I claim—

The design for a blank for a speculum-blade, substantially as shown and described.

In testimony whereof I have hereunto affixed my signature this 17th day of December, A. D. 1900.

CHARLES J. PILLING.

Witnesses:

ANDREW V. GROUPE,
H. T. FENTON.
